US00D580386S

(12) **United States Design Patent**
Cho et al.

(10) **Patent No.:** US D580,386 S
(45) **Date of Patent:** ** Nov. 11, 2008

(54) **CELLULAR PHONE**

(75) Inventors: **Yoo Seok Cho**, Yongin-si (KR); **Joung Young Joung**, Gyeonggi-do (KR); **Jeong Eun Yun**, Chungcheongbuk-do (KR)

(73) Assignee: **LG Electronics Inc.**, Seoul (KR)

(**) Term: **14 Years**

(21) Appl. No.: **29/267,901**

(22) Filed: **Oct. 25, 2006**

(30) **Foreign Application Priority Data**

May 24, 2006 (KR) 30-2006-0019311

(51) **LOC (8) Cl.** **14-03**

(52) **U.S. Cl.** **D14/138**

(58) **Field of Classification Search** D14/138,
D14/496, 341-347; 455/575.3, 575.1

See application file for complete search history.
